US0D1019408S

(12) **United States Design Patent** (10) **Patent No.:** **US D1,019,408 S**
(45) **Date of Patent:** **** Mar. 26, 2024**

(54) **CONTAINER**

(71) Applicant: **S. C. Johnson & Son, Inc.**, Racine, WI (US)

(72) Inventors: **Paul E. Furner**, Racine, WI (US); **Seth Frankel**, Arlington, MA (US); **Aaron Arcello**, Whitefish Bay, WI (US)

(73) Assignee: **S.C. JOHNSON & SON, INC.**, Racine, WI (US)

(**) Term: **15 Years**

(21) Appl. No.: **29/827,143**

(22) Filed: **Feb. 17, 2022**

(51) LOC (14) Cl. **09-01**

(52) U.S. Cl.

USPC **D9/542**; D9/560; D9/563

(58) **Field of Classification Search**

USPC D9/541-544, 546, 560, 563-574, 682,
D9/686, 687, 694, 530, 575; D24/197
CPC A45D 40/0068; B65D 1/0223; B65D
2501/0081; B65D 79/0084

See application file for complete search history.

(57) **CLAIM**

The ornamental design for a container, as shown and described.

DESCRIPTION

FIG. 1 is an isometric view of a top, front, and right side of an ornamental design for a container;

FIG. 2 is a front elevational view of the container of FIG. 1; FIG. 3 is a rear elevational view of the container of FIG. 1; FIG. 4 is a left side elevational view of the container of FIG. 1;

FIG. 5 is a right side elevational view of the container of FIG. 1; and,

FIG. 6 is a top plan view of the container of FIG. 1. The dash-dash-dash lines are included for the purpose of illustrating portions of the container that form no part of the claimed design.

1 Claim, 6 Drawing Sheets
